UNITED STATES PATENT OFFICE

127,791

DESIGN FOR A SPECTACLE FRAME

Frederick H. Fisher, Miami Beach, Fla.

Application March 21, 1941, Serial No. 99,765

Term of patent 7 years

To all whom it may concern:

Be it known that I, Frederick H. Fisher, a citizen of the United States of America, residing at Miami Beach, in the county of Dade and State of Florida, have invented a new, original, and ornamental Design for a Spectacle Frame, of which the following is a specification, reference being had to the accompanying drawing, forming part thereof.

In the drawing:

Figure 1 is a front elevational view of the spectacle frame, shown in my new design; and

Figure 2 is a top plan view of the same.

The essential features of my design reside in the portions shown in full lines, the broken lines shown on the nose bridge portion indicating an emblem.

I claim:

The ornamental design for a spectacle frame, substantially as shown and described.

FREDERICK H. FISHER.
